UNITED STATES PATENT OFFICE.

THOMAS MANEY, OF LOUISVILLE, KENTUCKY.

GUARD-RAIL FASTENER.

Application filed April 6, 1929. Serial No. 353,022.

This invention relates to an improvement in guard rail fasteners.

The present invention is an improvement on my United States Patent No. 1,639,524, of 5 August 16, 1927, and relates to the construction and disposition of the resilient filler interposed between the guard rail chair and the base of the guard rail.

The object of the improvement is to direct 10 the abrasive effect of a depression of the guard rail against the base of the guard rail instead of against the chair. This prevents an undue wearing away of the chair and greatly lengthens the life of the chair, al- 15 though the guard rails have to be removed at frequent intervals, since they are worn away by the wheels of the train and would be renewed regardless of any wearing away which may be caused by the resilient filler.

20 In the accompanying drawings:

Fig. 1 is a sectional view partly in side elevation showing the invention applied;

Fig. 2 is a transverse sectional view on the line 2—2 of Fig. 1; and

25 Fig. 3 is a similar view showing a slight modification.

The numeral 1 designates the main rail that is mounted upon the usual tie plate 2 and which may be seated on the tie 3, or 30 otherwise. Also carried on this tie plate 2 is a chair 4, which may be of any suitable form, the one illustrated being of the form shown in my Patent No. 1,713,878, May 21, 1929.

35 This chair is provided with an arm 5 formed integral therewith and which abuts against the head of the main rail 1, so as to brace the main rail. The chair may be of any suitable construction and the invention 40 may be used with different forms of chairs and is not limited to the form shown in the drawings, this being illustrated merely as a matter of convenience.

The chair 4 is provided with a seat 6, 45 within which the base 7 of a guard rail 8 fits and is mounted. The seat 6 formed in the chair is provided with a shoulder 9 disposed over the base flange 7 of the guard rail 8 to facilitate mounting of the guard rail 50 in the chair seat and at the same time to cause the upper portion of the chair to rigidly brace the guard rail.

In order to effectively hold the guard rail in the seat 6, after it has been disposed

therein, a resilient key 10 of the form best 55 shown in Fig. 2 is inserted between the shoulder 9 and the base flange 7 of the guard rail.

In the form shown in Fig. 2, this key is provided with a straight, smooth, and flat 60 portion 11, at the opposite ends of which portion shoulders 12 are formed, which terminate in bows 13, after which the ends are bent under the flat portion 11 toward each other and then toward the flat portion 11 65 as at 14. In this way, the ends of the resilient key bear against the base flange 7 of the guard rail, while that portion bearing against the shoulder 9 is flat. Consequently, 70 when a depression is given to the guard rail, the abrasive effect thereof will be directed against the base of the guard rail instead of against the shoulder 9 of the chair, which prevents a wearing away of the shoulder and distributes the wear over the base of the 75 guard rail, which is not so objectionable, because the guard rail must be renewed at intervals to compensate for the wearing away caused by the train wheels.

In the modified form shown in Fig. 3, 80 the effect of the resilient key 10' is the same. It is provided with a flattened portion 11', which terminates in an end shoulder 12' at one end and at the opposite end has the bow 13' which is bent back to form the 85 under spring end 14'. The spring action is the same and here also the wear will be distributed over the base flange of the guard rail and approximately at the center of the chair.

90 In this form, the spring is inserted and removed from the same end which permits the bow 13' to be made larger than the bows 13 in the form shown in Fig. 2, in which the spring may be inserted and removed 95 from either end.

I claim:

1. The combination of a guard rail, a chair for bracing said guard rail and having a space between it and a portion of the guard rail, and a resilient key inserted in said space for exerting pressure on the guard rail and chair, said key having a flattened portion bearing against the chair and an end portion bearing against the guard rail. 100

105 2. The combination of a guard rail, a chair for bracing said guard rail and having a space between it and a portion of the

guard rail, and a bow-shaped resilient key inserted in said space for exerting pressure on the guard rail and chair.

3. The combination of a guard rail, a chair for bracing said guard rail and having a space between it and a portion of the guard rail, a bow-shaped resilient key inserted in said space for exerting pressure on the guard rail and chair, said key having a side portion extending throughout the width of the contacting portion of the chair and having another side portion engaging a portion of the guard rail.

4. The combination of a guard rail, a chair for bracing said guard rail and having a space between it and a portion of the guard rail, and a bow-shaped resilient key inserted in said space for exerting pressure on the guard rail and chair, said key having a flat side extending throughout the width of the contacting portion of the chair and having an end portion engaging the guard rail and joined to the flat side by the bow at the ends thereof.

5. The combination of a guard rail, a chair for bracing said guard rail and hav-

ing a space between it and a portion of the guard rail, and a resilient key inserted in said space for exerting pressure on the guard rail and chair, said key having a flat side portion extending in contacting relation with the contacting portion of the chair throughout the width of said contacting portion, shoulders formed at the opposite ends of said straight portion and adapted to be disposed on opposite sides of the chair, and an end portion joined to the flat portion by a spring bow at the ends thereof, said end portion being adapted to bear against the guard rail.

6. A resilient key for exerting tension between a guard rail and chair therefor, and having a flattened or straight portion adapted to bear against the chair throughout the width of the contacting portion thereof and having an end portion joined to said straight portion by a resilient bow, said end portion being adapted to engage the guard rail.

In testimony whereof I affix my signature.

THOMAS MANEY.
